UNITED STATES PATENT OFFICE

2,458,198

CONTROL FOR SPILL PORTS FOR FREE-PISTON UNITS

David M. Poole, Summit, N. J., assignor to United Aircraft Corporation, East Hartford, Conn., a corporation of Delaware

Application April 15, 1944, Serial No. 531,308

8 Claims. (Cl. 230—56)

1

This invention relates to a free-piston engine-and-compressor unit and particularly to a control for the spill ports by which the effective volume of the compressor is adjusted.

The copending application of Cooper, Serial No. 531,301, filed April 15, 1944, describes a free-piston unit, the compressor cylinder of which has a number of rows of openings forming spill ports through which a part of the air in the compressor cylinder is discharged. A feature of this invention is an arrangement for controlling the ports.

When the unit is adapted for aircraft use, and therefore, subject to substantial variations in intake pressure, the unit can best be adapted to these variations by successive closing of the rows of ports. A feature of this invention is an arrangement by which the rows of ports may be individually and successively controlled.

Another feature of this invention is a control for the ports which is compact and will not seriously increase the space requirement for the unit. Another feature is the control of the ports by an axially movable band extending around the compressor cylinder.

Other objects and advantages will be apparent from the specification and claims, and from the accompanying drawings, which illustrate an embodiment of the invention.

Fig. 1 is a sectional view through a free-piston unit.

Fig. 2 is a fragmentary view of the activating mechanism for the inner bands.

The unit shown includes an engine cylinder having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10 through one or more nozzles 32. Air compressed in the air spring cylinders on the power stroke returns the piston assemblies. The assemblies are always maintained at equal distances from the center of the engine cylinder by a linkage, not shown.

Intake manifold 42, which extends around the compressor and engine cylinders conducts air to intake valves 44 in the heads of the compressor cylinders, through which air alternately enters opposite ends of the cylinders. The compressed air leaves the cylinder through discharge valves 46, also at opposite ends of the compressor cyl-

2

inders and passes into a central scavenging chamber 48 and end chambers 50 and 52. These chambers may be interconnected by a scavenging manifold, not shown.

Compressed gas from the scavenging chambers enters engine ports 54 and 56 which are uncovered by pistons 12 and 14 at the end of the power stroke, thereby permitting air to be blown through the engine cylinder. Gas and air in the engine cylinders are discharged through exhaust ports 58 into exhaust manifold 60.

Each compressor cylinder has a number of axially spaced rows of spill ports 62 which permit discharge of air from the cylinders without compression. The rows of ports are controlled by one or more bands 64 extending around the cylinder and movable axially to close the rows of ports successively, beginning with the end rows. Each cylinder preferably has an outer band 64 and an inner band 65 so that the inner and outer end rows may be closed before the other rows, and, by selective movement of the bands, the rows of ports may be closed or opened in sequence from opposite ends of the cylinder.

If the unit is used in aircraft, and is designed for altitude operation, the bands are moved so that all the rows of ports are open at sea level, and only a small volume of gas is compressed. As the density of the air decreases (at altitude) one or more of the rows of ports may be successively closed, beginning with the end rows to increase the effective volume of the compressor. The several rows of ports permit adaptation of the compressor to substantially any altitude or to any air density.

The bands may be moved manually or they may be moved mechanically. For example, as shown, the outer bands 64 may have inwardly projecting rods 68 carrying, on their inner ends, pistons 70 in a cylinder 72. For closing the spill ports, fluid under pressure enters the outer ends of the cylinder through a pipe 74 and fluid exhausts through a central pipe 76. If desired, a control mechanism may be used for admitting fluid selectively through pipe 74 or 76.

A similar control device may be used for moving the inner bands, the device operating independently of the controls for the outer bands 64. As shown, inner bands 65 have inwardly extending rods 78 carrying pistons 80 in a cylinder 82. Fluid is admitted to opposite ends of cylinder 82 through ports 84 to uncover the inner rows of ports. By admitting fluid to a central port 86, the pistons 80 are urged apart to close the inner

rows of ports successively from the inner ends of the compressor cylinders.

It is to be understood that the invention is not limited to the specific embodiment herein illustrated and described, but may be used in other ways without departure from its spirit as defined by the following claims.

I claim:

1. A free-piston unit including a compressor cylinder and a piston therein, said cylinder having a cylindrical wall with at least one row of circumferentially arranged ports extending therethrough, and a band surrounding, engageable with, and movable on the outer surface of said cylindrical wall to close or open said ports.

2. A free-piston unit including a compressor cylinder and a piston therein, said cylinder having a cylindrical wall with at least one row of circumferentially arranged ports extending therethrough, and a band surrounding, engaging with, and movable axially on the outer surface of said cylindrical wall for opening or closing the ports.

3. A free-piston unit including a compressor cylinder and a piston therein, said cylinder having a cylindrical wall with a number of axially spaced rows of ports extending through the wall and arranged circumferentially therein, and at least one band engageable with and movable axially on the outer surface of said cylindrical wall for opening or closing the rows of ports in a predetermined sequence.

4. A free-piston unit including a compressor cylinder and a piston therein, said cylinder having a cylindrical wall with a number of axially spaced rows of ports extending through the wall and arranged circumferentially therein, at least one band engageable with and movable axially on the outer surface of said cylindrical wall for opening or closing the rows of ports in a predetermined sequence, and means for moving said band axially along the outer surface of the cylinder wall.

5. A free-piston unit including an engine cylinder, opposed pistons in the cylinder, compressor pistons moving with the engine pistons, and opposed compressor cylinders for said compressor pistons located at opposite ends of the engine cylinder, said compressor cylinders each having a number of axially spaced rows of ports extending through the cylinder, each row extending circumferentially around the cylinder, a closure means on the outer surface of each cylinder movable to close the rows of ports, and means for moving the closure means on the opposed compressor cylinders simultaneously.

6. A free-piston unit including an engine cyl-

inder, opposed pistons in the cylinder, compressor pistons moving with the engine pistons, and compressor cylinders for said compressor pistons located at opposite ends of the engine cylinder, each of said compressor cylinders having a cylindrical wall having a number of axially spaced rows of ports, each row extending circumferentially around the compressor cylinder, and a band extending around each compressor cylinder and movable to open or close the ports.

15 7. A free-piston unit including an engine cylinder, opposed pistons in the cylinder, compressor pistons moving with the engine pistons, and compressor cylinders, each of said compressor cylinders having a cylindrical wall having a number of axially spaced rows of ports extending therethrough, each row extending circumferentially around the compressor cylinder, and a band extending around each compressor cylinder and 20 movable axially on the compressor cylinder for opening or closing the ports.

25 8. A free-piston unit including an engine cylinder, opposed pistons in the cylinder, compressor pistons moving with the engine pistons, and compressor cylinders, said compressor cylinders each having a number of axially spaced rows of ports, each row extending circumferentially around the compressor cylinder, and a band extending around each compressor cylinder and 30 movable axially on the compressor cylinder for opening or closing the rows of ports successively.
